UNITED STATES PATENT OFFICE.

MORAN O. TANNER, OF FARRELL, PENNSYLVANIA, ASSIGNOR OF TWENTY-FOUR ONE-HUNDREDTHS TO WILLIAM W. WYANT AND TWENTY-FOUR ONE-HUNDREDTHS TO WALLACE SCOWDEN, BOTH OF FARRELL, PENNSYLVANIA.

INTERNAL-COMBUSTION ENGINE.

Application filed January 28, 1922. Serial No. 532,378.

To all whom it may concern:

Be it known that I, MORAN O. TANNER, a citizen of the United States, residing at Farrell, in the county of Mercer and State of Pennsylvania, have invented certain new and useful Improvements in Internal-Combustion Engines, of which the following is a specification.

This invention has reference to internal combustion engines, and its object is to avoid timing gearing and to provide means whereby the timing of the engine, whether of the usual four cycle type or of multicycle type, is accomplished by mechanism of extreme simplicity, with a minimum of wearing parts and with positive guidance of the valves in their action.

The engine includes the usual form of cylinder and crank shaft and of valves for supplying fuel to the engine cylinder or cylinders, and means for properly operating the valves in timed relation to the reciprocation of the engine cylinder.

A valve operating means is also incorporated in the engine to cause the usual cycle of operations, in this case having relation to a four cycle engine, or which may or may not be of the multi-cylinder type greater in number than four.

While the explosion engine has more particular reference to the multi-cylinder type of explosion engines, in the following detailed description, the explanation of the engine for simplicity of description will be confined to a four cycle type of single cylinder construction, for, in adapting the invention to internal combustion engines of multi-cylinder type, it is merely necessary to enlarge the valve operating mechanism without any change in the principle of operation.

Considering the invention in its simplest form, there is mounted on the crank shaft of the engine, an irregular cylinder on which there are produced two ribs arranged side by side and at one point in the circumference of the cylinder, these ribs cross each other, and, at the point of intersection, there

is provided a crossing member, preferably of diamond shape and constituting a guide from one rib to the other at the crossing point so that the guide will oscillate from one rib to the other over the diamond-shaped or other junction.

The ribs and the joining guide are always above the surface of the cylinder, which has an irregularly conical surface and by means of the surface and the ribs formed thereon, the valve movements, causing the running of the engine are brought about.

The invention will be best understood from a consideration of the following detailed description taken in connection with the accompanying drawings forming a part of this specification, with the understanding that the invention is not confined to any strict conformity with the showing of the drawings, but may be changed and modified so long as such changes and modifications mark no material departure from the salient features of the invention as expressed in the appended claim.

In the drawings:—

Figure 1 is a vertical axial section of an internal combustion engine embodying the invention.

Fig. 2 is a section on the line 2—2 of Fig. 1, but omitting distant parts.

Fig. 3 is a section like that of Fig. 1, also omitting distant parts.

Fig. 4 is a section through the valve operating cam at right angles to the axis of rotation of the cam.

Referring to the drawings, there is shown an internal combustion engine 1, which may be of the usual upright type, in the basic portion of which there is journaled a crank shaft 2, which may follow the usual practice in internal combustion engines, and hence requires no particular description.

Erected on the basic portion 1, is an upright cylinder 3 having the usual water jacket 4, which, also, being of ordinary construction needs no especial description.

Within the cylinder 3, there is mounted a power piston 5 of usual construction, con-

nected by a pitman 6 with the customary crank 7 which may be formed on the crank shaft 2, the latter carrying the usual fly wheel 8 conveniently located within the casing 1.

So far as described, the structure of the internal combustion engine, need not depart to any material extent from explosion engines as they already exist.

10 On the shaft 2 there is a cam 9 formed with a concentric and an eccentric portion formed integral one with the other, as shown in Fig. 1. The eccentric portion of the cam is of irregular contour and its periphery is so formed as to provide two arcs 11^a and 11^b each having a different radius, but a common radial point, and a straight portion 11^c into one end of which one end of the arc 11^a merges, and the other end of this arc and said straight portion terminate by turning inwardly and then outwardly as at 11^d to merge into the ends of the arc 11^b. Upon the surface of each of these two portions, is formed an annular split rib 10 and 11 of triangular cross section, the ends of the rib 11 being positioned upon the straight portion 11^c and the ends of this rib are directed toward and spaced from the ends of the other rib at this point.

20 The cam 9, which is carried and operated by the shaft 2, is formed of what may be termed an outer continuous circular portion 9' and an inner substantially oval-shaped portion 9''. The outer portion 9' is set up 25 in a manner to have a continuous plane peripheral surface of varying width concentrically disposed with respect to the shaft 2, as at 10' and further with a bevelled peripheral surface of varying widths, as at 40 10''. The inner portion 9'' of the cam 9 has a substantially wide continuous plane peripheral surface 10''' arranged eccentrically with respect to the shaft 2 and with the major portion thereof offset with respect to the plane peripheral surface 10' of 45 the outer portion 9' and with the remaining part of the plane peripheral surface 10''' merging at one side into the plane peripheral surface 10' of the outer portion 9'. 50 The rib 10 traverses the plane surface 10' of the outer portion 9' and has its ends directed towards and spaced from one side of the frog 12. The rib 11 traverses the peripheral surface 10''' of the inner portion 9'' and has its ends directed towards and spaced from the other side of the frog 12.

Positioned between and spaced from the ends of the two ribs is a cross frog 12 which 60 is of pyramidal form and diamond-shaped at its base to facilitate the action of the structure.

Rising from the casing 1 alongside of the cylinder 3 is a valve cylinder 13. Within 65 the cylinder 13 is a reciprocatory piston

comprising two aligned valves 14 forming intake and exhaust valves with a packing ring 15 between them.

Leading through the cylinder 13 from points 16, 17 are ducts 19 and 20 opening 70 into the cylinder 3.

Fast to one end of the valves 14 is a piston rod 21 to which is attached one end of a connecting rod 22 having a ball and socket connection 23 with the rod 21. The end 75 of the rod 22 remote from the ball and socket connection 23 is formed into a head or guide 24, suitably shaped, as with a notch 25 to engage either track 10 or 11 and also to move along the sharp edge of the triangular portion of the track.

The rod 22 oscillates in a groove 26 thus causing a sidewise reciprocation of the rod 22 so as to freely move into engagement with either track 10 or 11 and from one to the other when propelled by the diamond 12.

In the construction shown in the drawings, it is material that the valve 14 be free to reciprocate for a limited distance, but be held against rotation. For this purpose, the piston rod 21 is provided with a longitudinal groove 27 in which engages a pin 28, which may be a through pin.

In order to maintain the head 25 in engagement with the ribs 10 and 11, there is 95 lodged in the cylinder 13 against the upper end of the pistons or valves 14, a spring 29 held removably in position by means of a cap screw 30, shown in Fig. 1.

The valves 14 are so arranged that they 100 perform a double function, one valve serving as an inlet valve and the other as an exhaust valve, but the two valves operate in unison to perform their functions.

The two valves 14 and the two ribs 10 105 and 11 perform double functions, simultaneously, so that the engine is greatly simplified in its construction and operation and the cost of construction is correspondingly reduced.

The ball connection 23 provides for taking up wear without necessitating the renewal of the rod extension 22.

What is claimed is:—

A valve actuating means for internal combustion engines comprising a cam carried and operated by the crank shaft of the engine and formed of a continuous circular outer and a substantially oval-shaped inner portion, said outer portion having a continuous plane peripheral surface of varying width concentrically disposed with respect to said shaft and further having a bevelled peripheral surface of varying width, said inner portion having a relatively wide continuous plane peripheral surface arranged eccentrically with respect to said shaft and having the major part thereof offset with respect to the plane peripheral surface of the outer portion and having the remaining 120

part thereof merging at one side into said plane peripheral surface of the outer portion, an oppositely bevelled frog integral with said inner and outer portions at the 5 point of mergence of the plane surfaces of the said portions, a rib traversing said inner portion and having its ends directed towards and spaced from one side of said frog, a rib traversing the plane surface of the outer portion and having its ends directed towards and spaced from the outer side of said frog, a valve actuating means travelling on said ribs, and a universal joint connection between said actuating means and the valve.

In testimony whereof, I affix my signature hereto.

MORAN O. TANNER.
